UNITED STATES PATENT OFFICE

LLOYD J. BROWN, OF EVANSTON, ILLINOIS, ASSIGNOR TO E. PAYSON SMITH, OF SPRINGFIELD, ILLINOIS

BRAKE-HANGER SUPPORT

Application filed April 10, 1926. Serial No. 101,044.

My invention more specifically stated relates to means for supporting the hangers of brakes of railroad cars; that is to say, the invention relates to means whereby the hangers or links are pendently supported in place on truck frames.

Brake hangers are usually supported from an integral portion of the truck side frame which are generally in the nature of apertured lugs cast integral with the steel side frame adjacent to the vertically disposed compression members thereof. These projections or lugs project inwardly from the side frame a distance sufficiently to bring them in line with the wheels of the truck and are intended to pendently support proper hangers. These hangers are generally in the nature of U-shaped links eyeleted at the ends to receive the supporting pins.

My invention contemplates a construction which will permit the use of the eyeleted U-shaped links, or the substitution and use of the closed links when desired, without necessitating alteration in the integral portions or lugs of the truck side frame; while at the same time providing a construction adapted to overcome the difficulties and objections heretofore encountered through the frictional contact and wear between the pins or links and the integral portions of the side frame.

The objects and advantages of my invention will be readily comprehended from the detailed description of the accompanying drawings, wherein:—

Figure 1 is a side elevation of a portion of a truck side frame provided with one form of my improved hanger support.

Figure 2 is a detail view taken substantially on the line 2—2 of Figure 1 looking in the direction of the arrows.

Figure 3 is a detail side elevation of a portion of the truck side frame with my improved hanger support shown in Figure 1 as viewed from the inner side.

Figure 4 is a detail sectional view taken on the line 4—4 of Figure 2 looking in the direction of the arrows.

Figure 5 is a perspective view of the pin or link keeper and supporting plate.

Figure 6 is a view similar to Figure 2 illustrating the use of the closed link type of hanger.

Figure 7 is a top plan of the construction illustrated in Figure 6.

Figure 8 is a view similar to Figure 2, illustrating a modified form of keeper and supporting plate.

Figure 9 is a sectional view taken on the line 9—9 of Figure 8.

Figure 10 is a perspective view of the upper end of the closed link used in Figure 8.

Figure 11 is a perspective view of the keeper and supporting plate employed in Figure 8.

The truck side frame at points adjacent to the vertical compression members 15, 15, on what may be termed the inner side thereof, is provided with inwardly disposed projections 16; the side of each projection disposed toward the wheel of the truck being provided with enlargements or lugs 17, 18 arranged in vertically spaced relation as more clearly shown in Figure 4. That is to say, the projection 16 is provided with an enlargement 70

or lug cut away transversely intermediate of the top and bottom or bifurcated so as to provide a socket for the reception of the hanger supporting pin or end of the link as the case may be. The cut away portion or distance 75

between the upper and lower lugs 17 and 18 is made sufficient to receive the wear and keeper plate or member 19, see Figure 5, which is adapted to either receive the supporting pin 20 when the eyeleted U-shaped 80

link is employed, or the upper end of the continuous link 21; the member 19 locking the same in place.

The bottom lug 18 at distances removed 85

from the ends thereof is cut away to provide the spaced end lug portions 22, 22 spaced sufficiently away from the intermediate portion of the bottom lug 18 to provide space for the sides of the suspending U-shaped link 23 in Figures 1 to 4, or the sides of the closed 90

link 21 shown in Figure 6.

With brake hangers as heretofore employed, because of the weight of the brake mechanism and constant movement thereof, considerable difficulty has been encountered 100

due to the wear between the link holding pin, or between the closed link when used, and the integral lug of the truck side frame, with the result that the brake beam and shoe are permitted to drop down and be suspended below the normal plane relative to the wheels. Such lowered relation between the brake and the wheel is objectionable because of the improper positioning of the brake shoe 10 relation to the wheel. Where the hangers are in direct contact with the lugs of the truck side frame, the wear soon necessitates the renewal of the entire truck side frame and thus, of course, entailing an excessive cost and expense aside from loss of time.

15 My invention contemplates means whereby the hangers will not only be properly supported and locked in place, but which will also relieve the integral portions of the truck side frame of any wear; while on the other hand the elements which are subject to wear may be readily replaced or renewed without necessitating a scraping of the truck side frame. To this end I have provided the keeper member or plate 19 shown in detail 20 in Figure 5, which may be of suitable tempered metal provided on its upper face with a groove 24 terminating short of the ends of the plate to provide the end wall portions 25, 25. The member 19 is preferably of length corresponding to that of the lugs on the side frame, with what may be termed the inner side of the plate cut away as at 26, 26 to provide the sockets which extend transversely of the plate and beyond the groove 24 substantially to the reinforcing rib portion 27 so as to provide a sufficient clearance for the enlarged or eyeleted ends of the U-shape hanger 23 and at the same time permit swinging movement of the hanger. Where the type 30 of supporting means shown in the first four figures of the drawings is employed, the groove 24 is adapted to receive the supporting pin 20 after the latter has been passed through the eyeleted ends of the hanger 23; the intermediate portion of the pin resting in the groove 24 of the intermediate portion 28 of the plate while the ends of the pin beyond the sides of the hanger will be disposed 35 beyond the sockets 26, namely in the ends of the groove 24. Longitudinal movement of the pin 20 is prevented by the end wall portions 25 of the plate.

40 After the hanger with the pin inserted therethrough has been put into place as described, the keeper plate or member 19 is then inserted between the upper and lower lugs or portions 17 and 18 as shown. The lower face of the upper lug 17 is preferably 45 shown formed arcuate at 29, at the point coincident with the groove 24 in the plate in order to provide a proper socket for the pin 20, or the upper end of the closed link 21 shown in Figure 6 and permit sufficient oscillatory movement.

The forward or outer ends of the lugs 17 and 18 at their intermediate portions are provided with vertically disposed registering openings with which an opening 30 in the keeper member 19 is adapted to register when the latter has been inserted in place. The registering openings are intended to receive a pin 31 which may be retained in place against accidental removal by means of a cotter-pin inserted through the opening 75 in the lower end thereof as shown at 32.

In Figures 6 and 7 I show the closed end or loop hanger 21 employed instead of the eyeleted U-shape hanger 23 and therefore obviating the use of the pin 20. The end of 80 the loop-hanger 21 is placed into the intermediate portion of the groove 24 of the keeper element 19 with the sides of the link extending through the cut away portions or slots 26 of the plate and between the main 85 part of the lower lug 18 and the end lug portions 22, 22, as shown in Figure 6 where the portion of the keeper plate at the left hand side of the figure is shown broken away and in section.

90 As is apparent from the drawings, my invention permits the ready substitution of one type of hanger or link for the other type without necessitating alterations in the truck side frame; while the keeper plate or member 19 has bearing support practically throughout its entire length, with the downward thrust of the supporting pin 20 or end of the link 21 all being received by the keeper member 19, so that wear on the lower lugs or integral 95 portions of the truck side frame is impossible. Furthermore, with this construction, assembly of the parts is not only easily made, but in the event of undue wear of the groove 24 in the keeper member 19 the plate may 100 be readily replaced, by simply removing pin 31 and sliding keeper member 19 out from between the upper and lower lugs 17 and 18, thereby freeing the pin 20 in the construction 105 shown in Figure 1, or the upper end of the link 21 in the construction of Figure 6. As the keeper member 19 may be given treatment not possible to be given to the truck side frame, it is evident that the keeper member 110 may be hardened to withstand the down thrusts and frictional contact with the supporting pin or end of the link as the case 115 may be.

120 In Figures 8 to 11, inclusive, I show another modification of my invention wherein the keeper plate or member is intended to not only receive all downward thrusts but also to take care of upward thrusts on the hanger links or supporting members; the construction involving a keeper plate or member 33 125 shown in detail in Figure 11. The keeper plate or member 33, like the keeper plates or members heretofore described, is intended to be inserted between the lugs 17 and 18 formed integral with the truck side frame 130

and vertically spaced apart so as to receive the keeper plate or member 33 therebetween. In the exemplification of this modification, the brake hanger is shown in the nature of a closed link or loop 34 which is substantially similar to the link 21 shown in Figure 6, except that the upper end thereof is reduced and made rectangular in cross section as shown at 35 in Figure 10 in order to be of less transverse dimensions than the other transverse dimensions of the link, namely the cylindrical portions thereof, in order to permit insertion of the link into the groove 36 formed in the keeper member or plate 33. The groove 36 is undercut from the upper face of the keeper plate 33 so as to provide the overhanging lip portion 37 thereby restricting the upper end of the groove or socket 36 to an extent less than the vertical dimensions or thickness of the end 35 of the link, with the result that the link 34 will be locked in the groove and held against upward movement while in normal suspended position. With the construction shown, it is apparent that the link 34 must be held at a suitable angle relative to the keeper member or plate 33, before the latter has been inserted between the lugs 17 and 18 in order to permit the reduced end 35 of the link to enter through the top portion of the groove or socket 36; the link being permitted to have free movement after it has been properly seated in the bottom of the groove or socket 36, as shown in Figure 9. The keeper member or plate 33, like the one shown in Figure 5, is also provided with the transverse or cut-away portions or slots 38, 38 extending transversely of the plate a distance slightly beyond the groove or socket 36 in order to give proper freedom to the link 34 for the necessary oscillatory movement; it being understood, of course, that the lower lug 18 is likewise provided with the transversely cut-away portions or sockets registering with the cut-away portions 38, 38. The outer end of the keeper plate or member 33 is provided with an aperture 39 adapted to register, when in place, with similar apertures in the top and bottom lugs 17 and 18 for the purpose of receiving the locking pin 31 which holds the keeper plate or member in place against accidental removal. It is apparent from the construction shown, that all downward thrusts are received by the keeper member or plate 33 in the bottom of the groove or socket 36, while any upward thrust encountered by the hanger is received by the overhanging lip 37 of the plate. As a result of this plate, no wear is encountered or frictional contact had with the lugs 17 and 18, namely the portions which are integral with the truck side frame; and therefore as wear is encountered by the constant swinging or oscillatory movement of the links the keeper plate as well as the link or hanger can be readily replaced without neces-

sitating the expensive loss heretofore encountered by the renewal of the truck side frames necessitated through the wear encountered in the integral lugs on the truck side frame.

While the modification in Figure 8 is shown as especially adapted for use with a continuous link or loop as shown in Figure 10, it is also evident that the keeper plate or member of Figure 11 is also adapted for use in connection with the U-shaped link shown in Figure 1, because the end of the keeper plate or member in Figure 11 is provided with an opening 40 through the end wall coincident with the end of the groove or socket 36, while the opposite end of the keeper plate or member is also shown provided with a socket at 41 coincident with the main socket or groove 36. The eyeleted ends of the U-shape hanger or link having been positioned in the cut-away portions or slots 38, a suitable supporting pin is then inserted through the aperture in the end of the keeper plate or member and passed through the eyes of the link; the pin being locked in place in any suitable manner against endwise movement.

In order to lock the supporting pin in place, I show one end of the keeper plate 33 provided with the lobes or ears 42, 42 disposed on opposite sides of the hole 40 into which the supporting pin (when a U-shaped hanger is used) is placed. After the supporting pin has been put into place, a cotter pin is inserted through the holes 43 of the lobes and therefore across the end of the supporting pin, preventing its withdrawal.

The various constructions disclosed in the drawings are assembled by first inserting the supporting pin 20 through the eyes of the link and then placing the pin in the groove 24 of the keeper member or plate 19 when employing the construction shown in the first four figures of the drawings; or by placing one end of the continuous link 21 in the groove 24 of the keeper member or plate 19, when employing the construction shown in Figure 6; or by tilting the link 34 at a proper angle relative to the keeper member or plate 33 so as to present the narrow edge or side of the reduced portion 35 toward the opening of the groove or socket 36 until the link has dropped into the lower part of the socket, when using the construction shown in Figure 8; after which the parts thus assembled are put into operative position by inserting the keeper plate into the slot or opening formed between the upper and lower lugs 17 and 18 of the truck side frame and then locking the keeper plate in position by inserting the retaining pin 31.

The various keeper plates, at what may be termed their rear or inner sides, are shown provided with an extension or lip 44, integral with the intermediate portion of the plates. The projection 16 on the truck side frame at a point coincident with the socket between

the upper and lower lugs 17 and 18 is provided with an opening as shown at 45 in Figure 4, adapted to receive the extension or lip 44. This not only provides additional bearing surface for the keeper plates, but it also prevents any possibility toward lateral shifting of the keeper plate about the locking pins 31.

The constructions shown not only securely hold the hangers or their supporting pins in place, but wear resulting from the constant chatter or vibration of the brakes is taken by the replaceable plates instead of being on the integral portions of the side frames as in constructions heretofore employed. The exemplifications in the drawings are believed to fully present the invention which has been described in terms employed for purposes of description and not as terms of limitation.

What I claim is:

1. A brake hanger support, comprising, in combination with vertically spaced lugs on the truck side-frame, a keeper plate adapted to be inserted between said lugs, the upper face of said plate being formed to retain the link and its hanger pin in place, the plate being transversely slotted for passage of the sides of the supporting link, and means whereby the plate is locked in place.

2. A brake hanger support, comprising, in combination with vertically spaced lugs on the truck side frame, a keeper member adapted to fit in between said spaced lugs, said keeper member being slotted transversely adjacent opposite ends thereof and provided on its upper face with a groove extending longitudinally thereof terminating short of the ends of the plate, and means whereby the keeper member is removably secured in place.

3. In a brake hanger support, a supporting plate provided with a groove extending lengthwise of the plate and undercut from the top surface so as to provide an overhanging thrust receiving lip.

4. In a brake hanger support, a supporting plate provided with a groove extending lengthwise of the plate and undercut from the top to provide an overhanging thrust receiving lip, the plate being slotted, intermediate of the center and both ends, transversely of the groove.

5. In a brake hanger support, the combination of a truck side-frame provided with a bifurcated lug, a pin and link supporting plate insertible between the bifurcations of the lug, the lower bifurcation and said plate at registering points being transversely slotted adjacent opposite ends, the plate being provided with a groove extending lengthwise thereof and intersecting the slots.

6. A brake hanger support, comprising a pin and link supporting grooved plate cut away transversely of the groove adjacent

opposite ends, and means whereby the plate is removably secured to a truck side frame.

7. In a brake hanger support, the combination of a truck side-frame provided with horizontally extending sockets disposed toward the truck wheels, a supporting plate insertible in said socket and provided on its upper face with a longitudinal groove, and means whereby the plate is secured in place.

8. A brake hanger support comprising a supporting plate, the upper face whereof is formed to provide a hanger pin and hanger link receiving groove, the ends of the plate being formed to prevent movement lengthwise of the groove, and means whereby the plate is secured in place on a truck side frame.

9. A brake hanger support comprising a plate, the upper face whereof is formed to provide a hanger and hanger pin receiving groove, with the ends of the plate formed to prevent movement lengthwise of the groove, the plate adjacent to the opposite ends being cut away transversely of the groove to provide link-side receiving sockets, and means whereby the plate is secured in place on a truck side-frame.

10. In a brake hanger support, a plate member, the upper surface whereof is provided with a longitudinally disposed groove, the member being slotted transversely from one side, and means whereby the member is secured in place on a truck side frame.

11. In a brake hanger support, a plate member provided with a groove extending lengthwise of the plate intermediate of the ends of the plate, the member being slotted transversely from the rear side and intersecting said groove, and means for removably securing the member to a truck side frame.

12. In combination with a truck side frame provided with vertically spaced lugs and an opening, a hanger and hanger pin holding plate adapted to fit intermediate of said lugs, grooved lengthwise and slotted transversely adjacent to the ends to provide hanger receiving passages, the portion of the plate intermediate of said slots being provided with an extension adapted to fit into the opening in the truck side-frame, and means whereby the plate is removably locked in place.

13. In a brake hanger support, a plate provided on its upper surface with an undercut groove so as to provide an overhanging thrust receiving lip, one end of the plate having an opening therethrough registering with the end of the groove, apertured ears on said end on opposite sides of the opening, the plate being provided with a pair of parallel slots extending from the rear side of the plate, and means whereby the plate is removably secured in place on a truck side frame.

14. A brake hanger support, comprising in combination with a laterally disposed projection on a truck frame, the projection being slotted transversely from one side to provide

a socket, the open end whereof is disposed toward the wheels of the truck, the inner vertical portion of the projection being provided with a slot of less length than the length of the socket and communicating with the inner end of the socket, a keeper and supporting member insertible in said socket, the upper face of said member being formed to receive the upper end of a link hanger and hanger supporting pin and permit oscillatory movement of the hanger, the inner side of said member having an extension adapted to fit into said slot at the inner end of the socket.

15. The combination with a truck frame provided with an inwardly extending projection slotted transversely from one side of said projection to provide vertically spaced walls, and a brake hanger, of a removable keeper plate adapted to fit into the slot sidewise, said plate being adapted to oscillatably hold the hanger in place, and means adapted to cooperate with the projection and said keeper plate for removably locking the latter in place.

25. 16. In a brake hanger support, the combination of a truck frame provided with a laterally disposed bracket having a slot disposed toward the wheels of the truck, a supporting member insertible sidewise into said slot said member being grooved longitudinally to receive a link hanger and a hanger supporting pin and having transverse slots for the sides of the hanger, and means for removably locking said member in the bracket.

35. 17. In a brake hanger support, a plate slotted transversely from one side of the plate adjacent to the ends, the upper face of the plate intermediate of said slots being dished while the ends of the plate are provided with pin receiving sockets in alignment with said dished portion, the socket of one end being disposed therethrough to permit longitudinal insertion of the supporting pin, said end of the plate being provided with means for locking said pin in place.

45. 18. In combination with a truck frame provided with a laterally disposed socket open at one side, a brake hanger, a supporting wear receiving plate having an undercut socket on one of its faces adapted to receive the brake hanger and to receive the upward and downward thrusts of the hanger, said plate being insertible edgewise into said socket, and means disposed through portions of the frame and through the plate whereby the latter is removably locked in place.

LLOYD J. BROWN.
